FIG.2

FIG.3

FIG.1

FIG.4

FIG.5

FIG.7

FIG.6

FIG. 1 is a view in side elevation of a holder for cocktail olives and the like, showing my new design;

FIG. 2 is a top plan view thereof;

FIG. 3 is a front elevational view thereof;

FIG. 4 is a rear elevational view thereof;

FIG. 5 is a bottom view thereof;

FIGS. 6 and 7 are further illustrations of my new design for holder for cocktail olives showing it in its normally supported positions of use upon the rim of a cocktail glass, which is indicated by dotted lines.

The characteristic features of my design thus resides in the rounded and rearwardly tapered animal-like body portion from which elongated and forwardly inclined legs depend and in the upwardly and forwardly curving hook-

shaped tail adjoining the smaller rear end of the body portion.

I claim:

The ornamental design for a holder for cocktail olives and the like, substantially as shown and described.
